PROTECTED TERMINAL

Joseph H. Staley, Columbus, Ind.

Application December 2, 1935, Ser. No. 52,539

3 Claims. (Cl. 173—332)

This invention relates to electrical terminals and has for its primary object the provision of means to cover the terminals against accidental contact therewith by operators, but at the same time permitting the connecting of said terminals to the devices without having to employ means for uncovering the terminals or making them available.

A further important object of the invention is to provide an operation whereby the terminal may be directly presented against the device to be connected and by simple pressure cause the terminal to be uncovered and connect with that device. Another important object of the invention is to provide a very simple as well as durable structure which may be produced at relatively low cost thereby permitting wide-spread use of the invention in order to further promote safety in making electrical connections where the terminals must necessarily be live.

These and other objects and advantages of the invention will become apparent to those versed in the art in the following description made in accordance with the accompanying drawings, in

25 which

Fig. 1 is a side elevation of a structure embodying my invention;

Fig. 2, an end elevation;

Fig. 3, a central longitudinal section on the 30 line 3—3 in Fig. 1;

Fig. 4, an end elevation of a modified form;

Fig. 5, a central longitudinal section on the line 5—5 in Fig. 4;

Fig. 6, a top plan view;

35 Fig. 7, a further modified form in central longitudinal section; and

Fig. 8, a central longitudinal section of the last modified form as engaged in a receiving receptacle.

40 Like characters of reference indicate like parts throughout the several views in the drawings.

In that form of the invention as shown in Figs. 1—3, I provide a body 10 made of some suitable insulating material, here shown as being cylindrical in shape, although not necessarily so, and having a central bore 11 entering therein from one end. I form a terminal 12 to have an annular flange 13 with a stud 14 extending axially therefrom.

50 This stud 14 is screwthreaded on its rear end and is also provided with a central bore entering from that end to receive therein the end of a conductor 15 which may be sweated or soldered in place and if desired further retained 55 by pressing inwardly a portion of the stud, as at

16, to be embedded in the conductor 15 to prevent its withdrawal from within that end of the stud. A sleeve 17 made of any suitable insulating material is formed to have a sliding fit within the bore 11 of the body 10 and further to have an axial bore through its rear end permitting the stud 14 to slide freely therethrough and screwthreadedly engage in the body 10 at the rear end of the bore 11 to have the conductor 15 extend outwardly from the rear end of the body 10. The sleeve 17 is further formed to have an enlarged bore through its major length receiving the flange 13 with a sliding fit therealong so that the outward travel of the sleeve 17 along the stud 14 is limited by the shoulder produced at the 5 end of the enlarged bore striking the rear side of the flange 13. A spring 18 is carried within the body 10 surrounding the stud 14 as a means for urging the sleeve 17 to its outermost position as indicated in Fig. 3. The length of the sleeve 20 17 is made to be such that it will carry therewithin the connecting end of the terminal 12.

In the form herein shown, the terminal 12 is provided with a transverse slit 19 to provide primarily for a resilient connection of the terminal 25 in the socket of the device (not shown) to which the terminal is to be applied. This slit 19 may be further employed as a means for revolving the terminal 12 by some such instrument as a screwdriver to cause the stud 14 to be firmly fitted by 30 its screwthreaded end on the body 10. The terminal 12 is made available throughout its length back to the flange 13 by direct pushing of the body 10 toward the device intended to receive the terminal so as to have the outer end of the sleeve 35 17 bear thereagainst and be carried back into the body 10 causing the terminal thereby to relatively extend outwardly therefrom. Of course, when the terminal is withdrawn from that device, the sleeve 17 will immediately move out and cover over the terminal end 12 under the influence of 40 the spring 18.

In the form of the invention as shown in Figs. 4—6, a pair of terminals 12 as indicated in the form shown in Figs. 1—3 are carried by a common 45 body 28 so that both terminals may be operatively carried by the same block or head. In this case, the head 28 is provided with a pair of bores 29 and 30, each receiving respectively the sleeves 17, springs 18 and the studs 14 therethrough to 50 screwthreadedly engage in the head. The forms of the invention so far described rely upon the sleeves being sufficiently extended beyond the outer ends of the terminals to prevent accidental contact of the operator therewith. In the form 55

shown in Figs. 7 and 8, the safety feature is carried still further. This form is similar to that in Figs. 1-3, but the terminal 32 corresponding to the terminal 12 is provided with a tip 33 made of insulating material and, further, is placed to extend from the sleeve 11 so as to serve as a pilot in entering the socket or female terminal 34. The tip 33 may be secured to the terminal 32 in any suitable manner, herein shown as being screwthreadedly attached.

When desired, means additional to the frictional grip may be employed to retain the terminal 32 in the female terminal 34. Such means may take the form of the customary spring grip 15 as indicated in Fig. 8, wherein the terminal 32 is provided with an annular groove 35 into which fall the shoulders 36 of the spring fingers 37 carried by the female terminal.

While I have herein shown and described my invention in the simplest form as now known to me, it is obvious that structural variations may be employed without departing from the spirit of the invention, and I, therefore, do not desire to be limited to that precise form beyond the 25 limitations as may be imposed by the following claims.

I claim:

1. In a connecting terminal, an insulating body having a bore open at one end and partially 30 closed at the other, the partially closed end having a threaded hole, an insulating sleeve slidably carried in the bore, said sleeve having an inside shoulder at its inner end, a metallic stud threaded at one end to screw into the threaded 35 hole in the insulating body and having a shoulder between its ends, said stud assembled axially of

the sleeve and body with the shoulder in the sleeve and a spring normally projecting the sleeve from the body into arresting contact with the shoulder on the stud.

2. In a connecting terminal, an insulating body 5 having a bore open at one end and partially closed at the other, the partially closed end having a threaded hole, an insulating sleeve slidably carried in the bore, said sleeve having an inside shoulder at its inner end, a metallic stud threaded at one end to screw into the threaded hole in the insulating body and having a shoulder between its ends, said stud assembled axially of the sleeve and body with the shoulder in the sleeve and a spring normally projecting the sleeve from 10 the body into arresting contact with the shoulder on the stud, said spring being carried in said bore behind said sleeve and surrounding said stud.

3. In a connecting terminal, an insulating body having a bore open at one end partially and 20 closed at the other, the partially closed end having a threaded hole, an insulating sleeve slidably carried in the bore, said sleeve having an inside shoulder at its inner end, a metallic stud threaded at one end to screw into the threaded hole in 25 the insulating body and having a shoulder between its ends, said stud assembled axially of the sleeve and body with the shoulder in the sleeve and a spring normally projecting the sleeve from the body into arresting contact with 30 the shoulder on the stud, and an insulating member on the outer end of the stud normally projecting a portion at least from said sleeve end to serve as a pilot.

JOSEPH H. STALEY. 35
